UNITED STATES PATENT OFFICE.

ALONZO E. RHOADES, OF HOPEDALE, MASSACHUSETTS, ASSIGNOR TO
DRAPE COMPANY, OF HOPEDALE, MASSACHUSETTS, A CORPORA-
TION OF MAINE.

LOOP-BANDING MACHINE.

SPECIFICATION forming part of Letters Patent No. 790,458, dated May 23, 1905.

Application filed March 6, 1905. Serial No. 248,587.

To all whom it may concern:

Be it known that I, ALONZO E. RHOADES, a citizen of the United States, and a resident of Hopedale, county of Worcester, State of Massachusetts, have invented an Improvement in Loop-Banding Machines, of which the following description, in connection with the accompanying drawings, is a specification, like characters on the drawings representing like parts.

This invention relates to machines for making loop-bands employed in spinning and other apparatus; and it has for its object the production of novel and efficient means to mark the loop-band while the same is distended, the marking of the band being effected at a predetermined distance from its loop end. As will be manifest, the marking of the bands is effected when the bands are under like conditions of tension, so that a series of such bands subsequently used in a frame and drawn to the mark and tied may be brought to the same tension.

I have illustrated my invention in connection with a well-known form of loop-banding machine, the essential portions of the band holding and twisting instrumentality being substantially as shown and described in United States patent to Weeks, No. 121,031, dated November 14, 1871. Heretofore in such machines the marking of the bands has been effected by a marker adapted to dip into marking liquid contained in a suitable reservoir, the marker being moved automatically out of the liquid and against the band at the proper time, the subsequent retraction of the marker usually effected by a spring causing the marker to dip suddenly and with considerable force into the liquid, tending to splash or throw some of it out of the reservoir. In my present invention, while the actuation of the marker to mark the band is effected positively and the retraction is caused by a spring, I have provided means to interrupt and retard such retractive movement of the marker so that the same enters the marking liquid quietly and with very little force, so that all tendency to splash or spill the liquid is entirely overcome.

The various novel features of my invention will be fully described in the subjoined specification and particularly pointed out in the following claims.

Figure 1 is a perspective view of a banding-machine embodying one practical embodiment of my invention. Fig. 2 is an enlarged detail, in rear elevation and broken out between its ends, of a portion of the machine to illustrate more clearly the marking means and the means by which the marker is actuated and controlled. Fig. 3 is a detail in rear elevation, showing the marker in engagement with the band to mark the same. Fig. 4 is a similar view, but showing the marker arrested or retarded in its retractive movement just about to enter the reservoir. Fig. 5 is a perspective view of the marker; and Fig. 6 is a transverse sectional detail on the line 6 6, Fig. 2, looking toward the left to show a portion of the retarding means which control the retractive movement of the marker.

Referring to Fig. 1, the bed-plate A, the shaft B, having fast and loose pulleys C and D thereon, the revolving head W, carrying the twisting-hooks G, (only one being shown,) the hooks being driven by well-known gearing mounted in the head, the fixedly-mounted guide-rods U, on which is slidably supported the loop holder or carriage J, having a loop-band hook H, the longitudinally-movable shipper-rod S, having the attached belt-fork E, the rod T, having an attached stop I to engage and prevent rotation of the revolving head W while the two halves of the band are being twisted preparatory to being doubled together, the arm L, fast on rod T, the pulley P, and weight Q are all substantially as in the patent referred to and operate as therein set forth. Collars O on the rods U serve as back-stops for cushioning-springs a^2 to act against the outer end of the loop-holder J when the weight Q is free to draw the same outward, as in the patent referred to. At a suitable point on the bed A is secured an upright bracket 1, having an upturned arm 2, carrying a horizontal pin 3, on which is loosely mounted the hub 4 (see Fig.

5) of the band-marker, herein shown as an arm 5, of stiff wire, secured to the hub and at its free end being bent down and then laterally, as at 6. The pin 3 and the lateral extension 6 are in parallelism and are located below and transversely to the band b^x when the latter is in position in the machine, the bracket being so located on the bed-plate A that when the marker is swung into operative position the part 6 thereof will contact with the band at a predetermined point from the loop thereof. A bowl-like reservoir 7 is mounted on the bracket 1 in such position that the marker may be swung on 10 its fulcrum 3 to dip the extension 6 into a marking liquid of suitable character (indicated at 8, Fig. 2) contained in the reservoir. Normally the marker remains in about the position shown in Fig. 2, and when moved to 15 operative position, Fig. 3, it will be manifest that the extension 6, loaded with marking material, will be pressed against the band b^x to mark the same at the proper point and at a predetermined distance from its loop then 20 held on the hook H.

A depending arm 9, suitably secured to the marker-hub 4, is pivotally connected with one end of a horizontal rod 10, slidably supported in bearings 11 12, fixed on the 25 shipper-rod S, as clearly shown in Fig. 2, and a collar 13, fast on the rod 10, near the bearing 12, has a depending foot 14, which loosely embraces the shipper-rod, serving as an additional guide for the rod 10. Between the bearing 12 and collar 13 a spring 30 15 is coiled around said rod 10, which spring serves by its expansion to retract the marker from operative position and to cause its extension 6 to dip into the marking liquid in 35 the reservoir. A second collar 16 is adjustably secured to rod 10 by a suitable set-screw 17, Fig. 2, and is in the path of movement of a lug 18 on the loop holder or carriage J when the latter is moved toward the 40 head W of the band holding and twisting instrumentalities. When the twisting of the band has moved the carriage to bring the lug 18 into dotted-line position, Fig. 2, the said lug engages collar 16 and slides the rod 45 10 to the right or toward the head W, and the marker is thereby swung positively into operative position to mark the band, simultaneously compressing the spring 15. At the same time a conical collar 19 on the rod 50 10 is moved past a swinging catch 20, fulcrumed on the bed-plate at 21, and the catch is swung inward by a weight 22 (see Fig. 6) behind the collar.

Referring to Fig. 2, the loop-holder J is 55 provided with a cam-plate having oppositely-inclined edges 23 24 and an intermediate flat portion 25, adapted to coöperate with the catch 20. The cam edge 23 serves to throw the catch outward and onto the flat portion 60 25 when the loop-holder is just beginning its

movement toward the head W, so that the portion 25 will hold the catch 20 out away from the collar 19, as in Fig. 2. As the loop-holder moves inward the catch will be released by the cam-plate, and it will then rest 70 against collar 19 until the lug 18 operates the marker, as has been described, and the catch swings in behind the said collar. The band having been marked, the shipper-rod is operated, as in the patent referred to, stopping 75 the operation of the twisting means when the band is finished. When the band is released from the hook H, the weight Q at once and quickly returns the loop holder or carriage J to starting position, and as the lug 18 re-treats the spring 15 acts to quickly retract rod 10 and the marker. Heretofore the latter has at once returned to the liquid, and the quick plunge thereinto tends to splash or spill the liquid, sometimes spattering the 80 marked band and also wasting the marking liquid. In my present invention, however, the retractive movement of the marker is arrested when the return movement of the rod 10 brings the end of collar 19 against the 85 catch 20, as shown in Fig. 6, the marker then being in the position shown in Fig. 4. The extension 6 is clear of the liquid, as will be manifest from an inspection of Fig. 4, and at the time the marker is arrested the loop-holder J has not reached the position shown in Fig. 2. As it continues its outward movement, however, the cam edge 24 engages the catch 20 and gradually swings the latter outward onto the flat portion 25, thereby withdrawing the catch from the collar 19 and permitting the spring 15 to complete the retractive movement of the marker into the reservoir. Such final retraction is so slight, however, and the extension 6 is so near the 95 surface of the marking liquid when it occurs that no splashing or spattering takes place, the effect of the retardation or arrest of the retraction of the marker being to cause it to dip quietly into the liquid.

My invention is not restricted to the precise construction and arrangement herein shown, as the same may be modified or rearranged by those skilled in the art without departing from the spirit and scope of my invention.

Having fully described my invention, what I claim as new, and desire to secure by Letters Patent, is—

1. In a loop-banding machine, a marker to mark the band, means to actuate it, a reservoir to contain marking liquid into which the marker is adapted to dip, and means to govern and retard retractive movement of the marker into the liquid, whereby splashing of the latter is prevented.

2. In a loop-banding machine, a marker to mark the band, means to actuate it, a reservoir to contain marking liquid into which the marker is adapted to dip, a spring to retract

the marker, and means to retard such spring-actuated movement of the marker and thereby prevent a sudden dip of the same into the marking liquid.

5. In a loop-banding machine, an oscillating marker to mark the band, positively-acting means to move the marker against the band, a spring to retract the marker, a reservoir containing marking liquid into which said marker is adapted to dip, and means to retard the spring-actuated retractive movement of the marker and thereby prevent splashing of the liquid.

4. In a loop-banding machine, a band holding and twisting instrumentality including a movable loop-holder, an oscillating marker, a reservoir containing marking liquid into which the marker dips, means governed by the movement of the loop-holder in one direction to swing the marker against the band to mark it, a retracting-spring for the marker, and means governed by opposite movement of the loop-holder to retard the retractive movement of the marker and thereby prevent its sudden entrance into the liquid.

5. In a loop-banding machine, a band holding and twisting instrumentality including a movable loop-holder, an oscillating marker, a reservoir containing marking liquid into which the marker dips, means governed by the movement of the loop-holder in one direction to swing the marker positively against and to mark the band, a spring to retract the marker, a stop to arrest such retraction before the marker dips into the marking liquid, and means to withdraw the stop from arresting position by or through the move-

ment of the loop-holder, to permit the marker to enter the marking liquid without splashing.

6. In a loop-banding machine, an instrumentality to hold and twist a band, combined with band-marking means, including a reservoir to contain marking liquid, a marker to mark the band while in the said instrumentality, means to effect positively operative movement of the marker, a spring to cause retraction of the marker and dip it into the marking liquid, and means governed by or through said holding and twisting means to interrupt retractive movement of the marker and prevent the same from dipping suddenly in the marking liquid.

7. In a loop-banding machine, a movable loop-holder, twisting means for the band, a swinging marker, a reservoir to contain marking liquid and into which the marker is adapted to dip, means actuated by or through movement in one direction of the loop-holder to operate the marker and mark the band, a spring to retract the marker as the loop-holder moves in the opposite direction and means to interrupt such retractive movement before the marker enters the reservoir and thereafter to permit the marker to dip easily into the marking liquid, to prevent splashing thereof.

In testimony whereof I have signed my name to this specification in the presence of two subscribing witnesses.
